T. N. HORNSBY, OF SIMPSONVILLE, KENTUCKY.

Letters Patent No. 68,509, dated September 3, 1867.

IMPROVEMENT IN THE MANUFACTURE OF CANNON.

The Schedule referred to in these Letters Patent and making part of the same.

TO ALL WHOM IT MAY CONCERN:

Be it known that I, T. N. HORNSBY, of Simpsonville, in the county of Shelby, and State of Kentucky, have invented a new and useful Improvement in Constructing Ordnance; and I do hereby declare that the following is a full, clear, and exact description thereof, which will enable others skilled in the art to make and use the same, reference being had to the accompanying drawings, forming part of this specification.

This invention relates to a new and improved mode of constructing wrought-iron and steel ordnance, which may be made in whole or in part of steel, wrought iron, or any other metals that are susceptible of being worked into ordnance in conformity to this improvement, which will be more readily understood by referring to the accompanying drawings, of which—

Figure 1 is a horizontal longitudinal view of my improved gun complete.

Figure 2 is a longitudinal section of the same.

Figure 3 is a view of the tube which forms the bore of the gun.

Figure 4 represents a plan of the scroll-sheet. This figure shows the shape of the sheet but not its proper proportion or size.

Similar letters of reference indicate like parts.

The sheet marked A, in the drawing, is of a breadth equal to the length of the tube B, and it forms the outside of the gun by being wrapped around said tube. It will be seen that one edge of the sheet is serrated, or that V-shaped pieces are cut from it, as indicated by *l*, along its entire length. This edge encloses the breech-pin of the gun. The opposite edge is then cut off in an inclined direction to C, making one end narrower than the other. This edge forms the spiral inclinations when the sheet is wrapped or wound upon the tube. The sheet is also notched in at the letter C deep enough to receive the muzzle-band upon the straight portion of the sheet when wound on the tube, as shown in fig. 1, and designated by the letter *d*. The portion between the letters *e* and *C* indicates the amount of wrapping for the muzzle of the gun. The margin extending from *e* to *f* is welded or brazed to the tube B, fig. 3, having first been bevelled down. It is then rolled around the tube while hot, and the serrated edge is hammered down over the inclined plane formed by the tube B and the breech-piece D. B represents the tube, fig. 3, of wrought iron or steel, made by welding together the two edges of a smooth, flat sheet of metal after having been rolled into a cylindrical form. The breech end of this tube is divided into four or more sections by the removal of V-shaped pieces, as indicated at *g*, in order that the remaining metal at this end may be bent down upon the breech-pin D, as shown. The letter *h* shows small cuts in the other end of the tube, which are made for convenience in manufacturing, and which may be filled up, if desired. D, fig. 2, represents the breech-pin. *a* indicates an inclined surface, which incline reduces its size to about one-half of its full diameter, and it is formed otherwise, as shown in the drawing. The part of the pin which has the inclined surface is driven into the tube B at *g*, as shown in fig. 2, and the divided portions are pressed or hammered down and made to clasp the breech-pin, as seen in the drawing. E represents the trunnions which are attached to the band F. G is the trunnion-brace, through the ends of which the trunnions pass. This brace or strap passes round the breech of the gun, as represented, and serves to hold the gun in place when it recoils from the discharge. H is the breech-band, which is thicker at the breech end than at the other, in order to fit the inclined surface formed by hammering and welding down the end of the tube B, and the serrated portion of the scroll-sheet A over the inclined portion of the breech-pin. This breech-band is composed of a sheet of metal wound round the breech and forming a scroll, the outer end of which is welded or brazed. After the breech-band is secured in its place, as before described, the cavity in the breech J is filled with melted metal of any kind which is sufficiently hard, and which will melt at a less degree of heat than the metal of the gun, in order to permeate the interstices and present a mass of solid metal to the inner surface of the breech-band H.

By this method of manufacture the liability of the gun to flaw is greatly lessened, and it greatly exceeds the proportionate strength of guns of the same calibre which are cast. It combines strength, lightness, and cheapness of construction, and they can be manufactured with great rapidity.

Having thus described my invention, what I claim as new, and desire to secure by Letters Patent, is—

Constructing cannon, in the manner described and of the several parts specified, consisting of the tube B, having notches *g* *h*, notched sheet A, bands *d* F, breech-piece D, trunnion-brace G, breech-band H, and breech J, as herein set forth.

T. N. HORNSBY.
